(57) **CLAIM**

The ornamental design for a cab of a drilling vehicle, as shown and described.

DESCRIPTION

FIG. 1 is a front perspective view of a cab of a drilling vehicle;

FIG. 2 is a rear perspective view thereof;

FIG. 3 is a side view thereof;

FIG. 4 is an opposite side view thereof;

FIG. 5 is a front view thereof;

FIG. 6 is a rear view thereof; and,

FIG. 7 is a top view thereof.

The broken lines in the figures are for illustrative purposes only and form no part of the claimed design.
